UNITED STATES PATENT OFFICE.

HENRY J. KLITSCH, OF EAST MAUCH CHUNK, PENNSYLVANIA.

HORSESHOE-CALK.

1,244,098.

Specification of Letters Patent.

Patented Oct. 23, 1917.

Application filed March 20, 1916. Serial No. 85,501.

To all whom it may concern:

Be it known that I, HENRY J. KLITSCH, a citizen of the United States, residing at East Mauch Chunk, in the county of Carbon and State of Pennsylvania, have invented certain new and useful Improvements in Horseshoe-Calks, of which the following is a specification, reference being had to the accompanying drawings.

10 This invention relates to an improved horseshoe calk and has for its primary object to provide simple and effective means for securely holding the calk in the shoe bar.

15 It is a more particular object of the invention to provide an improved form of calk which will effectively bite or grip into the ground surface, said calk having a reduced stud formed on one end provided with a key-receiving groove to receive a key formed 20 in the shoe, and a reinforcing rib formed on one side of the calk body in line with said groove.

25 It is a further general object of the invention to provide a device of the above character which is exceedingly simple in its construction, may be readily applied in practical use by the ordinary blacksmith, and is highly efficient and reliable in operation.

30 With the above and other objects in view, my invention consists in the novel features of construction, combination and arrangement of parts to be hereinafter more fully described, claimed and illustrated in the accompanying drawing, in which,

35 Figure 1 is a plan view of a horseshoe, partly in section, showing my improved calk applied thereto;

Fig. 2 is a vertical sectional view on line 2—2 of Fig. 1; and

40 Fig. 3 is a perspective view of the calk.

Referring in detail to the drawing, 5 designates the horseshoe bar which may be of any desired or ordinary form and construction, and this bar is provided at opposite 45 sides of the toe portion and in each of the heel ends with an opening 6. These openings taper longitudinally from the under side of the shoe to the hoof-engaging face thereof, and upon the bottom face of the shoe bar a raised boss 7 surrounds each of the openings 6. Upon the wall of each opening 6, at one side thereof, a longitudinal V-shaped rib or wedge 8 is formed.

45 The calk is preferably in the form of a single steel casting having a relatively wide body 9 formed with a sharpened gripping

edge 10. Upon the base of this calk body, a longitudinally extending, tapering shank 11 is formed. This shank is provided with a longitudinal groove or channel 12 conforming in shape to the rib 8. The calk body 9 gradually decreases in thickness or tapers from its base end to the cutting edge 10 thereof, and one side face of this calk body is curved longitudinally, as at 13, to provide 60 a concave surface portion adjacent the base end of said body and a convex surface adjacent to its cutting edge 10. It is to be observed that the cutting edge 10 is disposed at one side of the longitudinal axis of the calk 65 and opposite to that upon which the rib or key-receiving channel 12 is formed, so that the pressure upon each cutting edge of the calk will tend to force the shank 11 laterally and into tight wedging engagement upon the 70 rib 8. Upon the concave surface, centrally thereof and in longitudinal alinement with the channel 12 in the tapering shank 11, a tapering reinforcing rib or web 14 of V-shaped form in cross-section, is formed. 75 This rib reinforces the reduced side of the calk body and prevents bending or distortion of said body. The rib 14 is also inwardly inclined with its larger end at the top of the calk body 9 and flush therewith, 80 said upper end of the rib being adapted for contact with the bottom face of the shoe bar or more particularly the boss 7 surrounding 85 an opening 6.

In the operation and use of the invention, 90 when the shoe is formed the ribs 8 are formed in the opening provided in the shoe bar by means of a suitable tool. The calks are then arranged in position, the shanks 11 being fitted into the respective openings and 95 the ribs 8 engaging in the V-shaped grooves 12. The calks are tightly driven into the openings until the wider base end of the calk body bears upon the boss 7 of the shoe bar. In the use of the calk, the base thereof 100 affords a broad bearing surface against the reinforcing boss 7 of the shoe bar, and the rib 14 materially strengthens the relatively thin edge of this base portion of the calk. The longitudinal pounding pressure upon 105 the calk drives the stud or shank 11 more securely into the opening 6 into wedging engagement with the rib 8. In this manner, it will be seen that the calk will at all times be securely held in connection with the shoe 110 bar without the necessity of employing additional fastening means therefor. The device

is exceedingly simple in its construction and the calks may be very easily and quickly applied to the bar in position for use.

While I have shown and described the preferred construction and arrangement of the several features of the device, it will be understood that the same is susceptible of considerable modification therein; and I, therefore, reserve the privilege of adopting all such legitimate modifications as may be fairly embodied within the spirit and scope of the invention as claimed.

Having thus fully described my invention, what I desire to claim and secure by Letters Patent is:—

1. The combination with a horseshoe having a longitudinally tapering opening therein provided with a V-shaped rib on its wall, of a calk having a tapering shank projecting longitudinally from the calk body and provided with a V-shaped groove to receive said rib, said calk body gradually tapering in thickness from said shank to its other end

and having its gripping edge disposed at one side of the longitudinal axis of said shank, and a longitudinally extending V-shaped reinforcing rib formed on the side of the calk body in longitudinal alinement with the groove in said shank, said rib being positioned at the upper portion of the calk body and inclined inwardly with the larger end flush with the upper end of the body.

2. The combination with a horseshoe having a series of open-ended sockets; a plurality of calks, each having a shank, said shanks being each provided with a top-opening slot formed in the side thereof; and a plurality of wedge-shaped members rigidly mounted in said sockets for engagement by said slots.

In testimony whereof I hereunto affix my signature in the presence of two witnesses.

HENRY J. KLEITSCH.
